WILLIAM SCOTT, OF MEDFORD, MASSACHUSETTS.

VACUUM SYSTEM.

1,227,497.

Specification of Letters Patent. Patented May 22, 1917.

Application filed September 11, 1916. Serial No. 119,475.

To all whom it may concern:

Be it known that I, WILLIAM SCOTT, a citizen of the United States, residing at Medford, in the county of Middlesex and 5 State of Massachusetts, have invented certain new and useful Improvements in Vacuum Systems; and I do hereby declare the following to be a full, clear, and exact description of the invention, such as will enable others skilled in the art to which it 10 appertains to make and use the same.

The invention relates to vacuum systems of the type employed for maintaining a substantially uniform head on flowing liquid, 15 and more particularly to vacuum systems of this type for supplying gasolene to carburetors of internal combustion engines.

The object of the invention is to improve the construction, organization, and mode of 20 operation of vacuum systems of the above type, in order to produce a more simple, efficient and durable vacuum system than has heretofore been produced. This object is accomplished in the improved vacuum 25 system described in the following specification and particularly pointed out in the appended claims.

The preferred form of the invention is 30 illustrated in the accompanying drawings, in which Figure 1 is a central sectional elevation of the intake and discharge chambers of the vacuum system, their connection with the intake manifold of an internal combustion engine being shown diagrammatically, and Fig. 2 is a top plan of the vacuum 35 valve.

In the vacuum system illustrated in the drawings the explosion fluid or gasolene is drawn into an intake chamber 5 through an 40 intake passage 6 from a source of supply located below the level of the device; and when a predetermined amount of gasolene has been drawn into the intake chamber, it is discharged into a discharge chamber 7 45 from which it flows by way of the outlet 8 to the carburetor of the internal combustion engine, in connection with which the vacuum system is employed in order to maintain a substantially uniform head on the gasolene 50 as it flows to the carburetor. The gasolene is drawn into the intake chamber by the vacuum created therein by the intake manifold 9 of the engine. The intake manifold is connected with the intake chamber by 55 means of a vacuum pipe 10 which screws into a threaded hole in the upwardly extend-

ing portion 11 of a centrally-disposed boss 12 in the cap 13. The intake chamber is inclosed at its sides by a cylindrical glass tube 15, at its bottom by the upper side 60 of a flanged partition plate 16, and at its top by the flanged cap 13. Tight joints between the tube and the plate, and between the tube and the cap, are secured by means of the leather gaskets 17 and 18 respectively. 65 The glass tube is held against the plate, and the cap is held against the tube by means of a hollow rod 20 which screws into the plate, and onto the upper end of which the cap 13 screws. In the boss 12 of the 70 cap 13 is a vacuum passage 21 which leads from the intake chamber to a narrow throat 22 which connects the vacuum pipe 10 with a valve chamber or guideway 23. It will be observed that the upper end 24 of the 75 throat 22 is contracted; this contraction is for the purpose of retarding the vacuumizing of the intake chamber to thereby prevent the ebullition of the gasolene as it is drawn into the chamber. The intake passage 80 25 is formed in the partition plate 16, and is normally closed by a ball check valve 26 which is seated in a recess 26, and is held from displacement therefrom by a clip 27. Located within the intake chamber is a float 85 28 by which the operation of the apparatus is controlled. The float is provided with a hollow axial stem 29 which loosely embraces the hollow rod 20, and the float is thereby guided in its up and down movements. 90 When a predetermined amount of gasolene has been received into the chamber, a vacuum valve 30 is raised up to and held against the lower face of the downwardly extending portion 14 of the boss 12. In the upper 95 face of the valve is formed a groove 31 with which the vacuum passage 21 registers, and the vacuum valve 30 is held up against the boss 12 by the suction created in the vacuum passage 21 and in the groove 31 by 100 the engine manifold. The vacuum valve consists of a disk provided with lateral ears 32 having holes to receive two pins 33 rising from the float and passing loosely through the holes in the ears; the vacuum 105 valve is also provided with a sleeve 34 which loosely embraces the rod 20, and is free to move thereon. The sleeve 34 prevents the vacuum valve from cramping in its movement on the rod 20. As the gasolene in the 110 intake chamber is discharged, the float descends until the heads of the pins 33 engage

the top of the vacuum valve, whereupon it is disengaged from the boss. In the cap 13 is a hole 35 closed by a plug 36, through which gasolene may be poured into the intake chamber in case it is desired so to do.

5 The discharge chamber 7 is located beneath the intake chamber. The under side 37 of the partition plate 16 forms the top of the discharge chamber; a cap 38 forms its bottom, and a glass tube 39 forms its sides. 10 The upper edge of the glass tube 39 is seated against a flanged rim 40 extending downwardly from the partition plate. The glass tube 39 and the cap 38 are held in position 15 with relation to the partition plate by means of a screw 41 which passes tightly through a hole in a centrally-disposed boss 42 in the cap 38 and screws into a centrally-disposed boss 43 depending from the under side of 20 the partition plate. Gaskets 44 and 45 afford tight joints between the glass tube 39 and the partition plate 16 and the cap respectively. In the cap 38 is the outlet 8 through which 25 the gasolene passes to the carburetor of the engine. The intake chamber and the discharge chamber are connected by a discharge 30 passage 46 in the boss 43. The lower end of the discharge passage 46 is formed in the upper end of the screw 41, and discharges the 35 gasolene into the discharge chamber by way of the holes 47; and the upper end of the discharge passage is in the lower end of the hollow rod 20 and receives the gasolene from the intake chamber by way of the slots 48 in the rod 20. The discharge passage 46 is normally closed by a discharge valve 50 which is seated in the boss 43. The discharge valve is loosely connected by a pin 51 with the lower end of the valve stem 52, which 40 is located within and is guided in its movements by the hollow rod 20. The pin connection between the discharge valve 50 and valve stem 52 affords provision by which the valve may center itself on its seat. The air 45 in the discharge chamber is kept at atmospheric pressure, by means of a vent 53, which is in the form of a tube screwed into a hollow boss 54 projecting from the periphery of the partition plate.

50 The discharge valve 50 is adapted to be actuated to open the discharge passage to permit the gasolene to flow from the intake chamber into the discharge chamber, when a predetermined amount of gasolene has 55 been drawn into the intake chamber. In the present invention use is made of the vacuum creating means for unseating the discharge valve; and for this purpose a valve 55 is connected with the upper end of the valve stem 52 in the same manner as the discharge 60 valve 50 is connected with the lower end of the valve stem. The valve 55 slides snugly in the guideway 23 formed in the boss 12. The valve stem 52 with its connected valves 65 is of such weight that, while the vacuum

valve is not in contact with the lower face of the lower portion 14 of the boss 12, the suction action of the engine manifold is insufficient to lift the valve 55 (the space above the valve being vented as it were through the 70 vacuum passage 21); but as soon as the vacuum valve has been drawn into contact with the lower face of the boss 12, thereby closing the vacuum passage 21, the force of the suction action then exerted upon the 75 valve 55 is sufficient to lift it up against its valve seat 56 at the upper end of the guideway 23. The lifting of the valve 55 against its seat unseats the discharge valve. When the valve 55 has been drawn up against its 80 seat, a necked-down or reduced portion 57 of the valve is brought into alignment with the horizontal portion of an air passage 59, which passage opens at one end into the atmosphere and at the other into the intake 85 chamber and is normally closed by the valve 55. In this position of parts the vacuum in the intake chamber is broken and gasolene flows freely from it into the discharge chamber. 90

When the internal combustion engine is set in operation, it creates a vacuum in the intake manifold 9, with the result that the air in the intake chamber is exhausted by way of the vacuum passage 21, as a result 95 of which the gasolene in the source of supply, being under atmospheric pressure, flows into the intake chamber by way of the intake passage 6 and during this time no gasolene flows out of the intake chamber, the 100 discharge valve 50 remaining seated. As the gasolene flows into the intake chamber, it raises the float 28, and as the float rises the vacuum valve 55 approaches the lower face of the boss 12, until finally the space 105 separating the vacuum valve from the boss is so small that the suction action of the intake manifold suddenly slaps the vacuum valve tight against the under side of the boss 12, thereby stopping the exhausting of 110 the intake chamber. As soon as the vacuum valve is drawn up against the under side of the boss 12, the suction action of the intake manifold is exerted upon the valve 55 and lifts it and holds it in engagement with its 115 seat. The lifting of the valve 55 opens the air passage 59 thereby breaking the vacuum in the intake chamber and stopping the flow of gasolene into it, and at the same time it unseats the discharge valve, thereby permitting the gasolene in the intake chamber, now under atmospheric pressure, to flow by gravity into the discharge chamber. The gasolene flows into the discharge chamber from the intake chamber, by way of the 120 slots 48, into the upper end of the discharge passage 46, thence by the slotted sides 60 of the discharge valve into the lower end of the passage, and out into the discharge 125 chamber through the holes 47. From the 130

discharge chamber the gasoline passes by way of the outlet 8 to the carburetor of the engine. As the gasoline flows from the intake chamber into the discharge chamber, 5 the float gradually settles until the heads of the pins 33 engage the upper surface of the vacuum valve. Thereupon, as the float continues to settle, owing to the depletion of the gasoline in the intake chamber, the 10 vacuum valve is suddenly disengaged from the boss 12, and the vacuum above the valve 55 being vented by the vacuum passage 21 and the open air passage 59, the valve 55 falls thereby allowing the discharge valve 50 to fall upon its seat, which closes the discharge passage. As the valve 55 descends, its reduced portion 57 passes beyond the air passage 59, so that the air passage is effectually closed. Thereupon the process 15 of exhausting the intake chamber is recommenced and the gasoline flows in as before. If for any reason the valve stem 52 should remain in raised position after the unseating of the vacuum valve 30, the under surface 20 of the float will presently come into engagement with the outwardly extending ends of the pin 51, by which the discharge valve is secured to the valve stem 52, and the weight of the float will operate to tend 25 to move the valve stem.

It will be recognized from the description of the improved vacuum system forming the subject-matter of the present invention, that in construction it is simple, being free from 35 springs and such other parts as are liable to become inoperative by reason of continued use, and, therefore, that it constitutes a highly efficient and durable system which can be cheaply manufactured.

40 Having thus described the invention, what is claimed is:

1. A vacuum system for maintaining a substantially uniform head on flowing fluids, having, in combination, an intake chamber, an inlet passage thereto, a discharge passage therefrom, means for vacuumizing the chamber, a vacuum passage leading into the chamber through which it is vacuumized, an air passage connected with the atmosphere and with the intake chamber normally closed, means for closing the vacuum passage when a predetermined amount of fluid has been brought into the chamber, and means actuated by the vacuumizing 45 means upon the closing of the vacuum passage for opening the air passage to permit the chamber to be under atmospheric pressure.

2. A vacuum system having, in combination, an intake chamber, an inlet passage through which fluid is drawn into the chamber, a discharge passage from the chamber normally closed, a vacuum passage, means for vacuumizing the chamber through the 50 vacuum passage, an air passage connected with the atmosphere and with the chamber normally closed, means controlled by the amount of fluid in the chamber for closing the vacuum passage, and means controlled by the vacuumizing means for opening the air passage and simultaneously therewith the discharge passage.

3. A vacuum system for maintaining a substantially uniform head on flowing fluids having, in combination, an intake chamber 75 provided with intake and discharge passages, a vacuum passage leading into the chamber through which it may be vacuumized, means for vacuumizing the chamber, a normally closed air passage leading from 80 the atmosphere into the chamber, a float, a valve actuated by the float to close the vacuum passage when a predetermined amount of fluid has been drawn into the chamber, and a valve normally closing the air passage 85 actuated by the vacuumizing means upon the closing of the vacuum passage to open the air passage.

4. A vacuum system having, in combination, an intake chamber provided with an inlet passage through which fluid is drawn into the chamber, a discharge passage through which the fluid is discharged from the chamber, means for vacuumizing the chamber, a normally closed air passage connected with the atmosphere and with the chamber, means for closing the vacuum passage when a predetermined amount of fluid has been brought into the chamber, and means disconnected from the vacuum valve 90 and acting independently thereof controlled by the vacuumizing means for opening the air passage when the vacuum passage is closed.

5. A vacuum system having, in combination, an intake chamber, a plate forming the bottom of said chamber, an inlet passage in said plate through which fluid is drawn into the chamber, a discharge passage in said plate through which the fluid is discharged from the chamber, a cap forming the top of said chamber, a vacuum passage in said cap through which the chamber is vacuumized, an air passage in said cap connected with the atmosphere and with the intake chamber, a guideway crossing the air passage, a valve for normally closing the air passage adapted to slide in the guideway and having a reduced portion, vacuumizing means connected with the vacuum passage and with the guideway for vacuumizing the chamber, a hollow rod connecting the cap with the plate, a discharge valve adapted to slide in said rod for normally closing the discharge passage, a valve stem connecting the discharge valve 105 with the first named valve, a float adapted to be guided by the hollow rod for controlling the amount of fluid to be received into the chamber, and a vacuum valve loosely connected with the float for closing the vac- 110

uum passage when a predetermined amount of fluid has been drawn into the chamber, said air passage valve being adapted to be actuated by the vacuumizing means to bring its reduced portion opposite the air passage and simultaneously therewith to actuate the discharge valve.

6. A vacuum system for maintaining a substantially uniform head on flowing fluids, comprising an intake chamber, an exhaust passage therefrom, means for exhausting the air from the intake chamber, an inlet through which fluid passes into the intake chamber, means for closing the exhaust passage when a predetermined amount of fluid has passed into the intake chamber, a discharge chamber, a discharge passage connecting the two chambers, and a valve for normally closing the discharge passage, 20 adapted to be actuated by the intake chamber exhausting means upon the closing of the exhaust passage.

7. A vacuum system for maintaining a substantially uniform head on flowing fluids, comprising an intake chamber for receiving fluid, a float in the intake chamber, a discharge chamber, a passage between the two chambers, a valve for normally closing the passage, means for creating a vacuum in the intake chamber to cause it to receive fluid, and means operated by the vacuum creating means for opening the valve in the passage to permit the fluid to flow from the intake chamber into the discharge chamber 35 when the float has risen to a predetermined height.

8. A vacuum system for maintaining a

substantially uniform head on flowing fluids, comprising an intake chamber having an inlet through which fluid is adapted to flow into the intake chamber, a vacuum passage, means for creating a vacuum in the intake chamber, a float for closing the vacuum passage when a predetermined amount of fluid has been drawn into the intake chamber, a 40 discharge chamber, a discharge passage between the two chambers normally closed, and means actuated by the vacuum creating means for opening the discharge passage substantially simultaneously with the closing 45 of the vacuum passage.

9. A vacuum system for maintaining a substantially uniform head on flowing fluids, comprising an intake chamber, means for drawing the fluid into the intake chamber, 50 a float in the intake chamber to stop the flow of fluid into the chamber when a predetermined amount of fluid has been drawn into the chamber, a discharge chamber, a passage between the two chambers normally closed, and means controlled by the means for drawing the fluid into the intake chamber for opening the passage.

10. A vacuum system for maintaining a substantially uniform head on flowing fluids, comprising an intake chamber, means for drawing the fluid into the intake chamber, a discharge chamber, a passage between the two chambers normally closed, and means controlled by the means for drawing the fluid into the intake chamber for opening 65 the passage.

WILLIAM SCOTT.
